CROWN CAP

Coleman A. Beeson, Baltimore, Md.

Application October 9, 1946, Serial No. 704,551

5 Claims. (Cl. 215—46)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to containers and particularly to removable crown caps for same.

The conventional cap for a bottle or can held on by a crimped-edge arrangement has the disadvantage of requiring a special tool of some nature for its removal, so as to get at the contents. Where such tool is not available, and the contents have to be removed, the general tendency of the user is to mutilate the container, or in the case of a bottle, to break off its neck. This causes a loss of the contents, and endangers the user or those in the vicinity. In addition, there is the expense involved in having to have such a tool manufactured for this specific purpose.

It is therefore an object of the invention to provide a new and improved crown cap for a container that will avoid one or more of the disadvantages and limitations of the prior art.

Another object of the present invention is to provide a new and improved crown cap for a container that may be readily removed by a common coin or similar small object usually available in the pocket of a prospective user, or nearby.

An additional object of the invention is to provide a new and improved crown cap for a container, that may be removed in an effective manner and expeditiously. Other objects will become apparent as the invention is more fully explained.

For a better understanding of the invention and its objects, reference is made to the appended drawings and the description following, wherein a particular form of the invention is detailed by way of example, and the scope thereof is particularly pointed out in the claims.

Referring to the drawings,

Figure 1 shows in perspective a crown cap embodying the invention and applied to a bottle, also indicating the method of removing the cap by means of a small coin.

Figure 2 is a diametrical section through the crown cap and bottle shown in Figure 1.

Figure 3 is a plan view of the cap.

Similar reference numerals designate similar parts throughout the several figures.

In the particular structure shown, a pressed sheet metal crown cap 10 with a down-turned scalloped edge or skirt 11 and rounded peripheral rim 12 is shown assembled to a bottle 18. The bottle mouth is formed with the usual peripheral

2

bead 16 therearound, and the inwardly extended convolutions of the skirt 11 engage under this bead with a clamp effect as is common in prior crown caps. A deepened groove 13 extending diametrically along the middle portion of the cap for a distance of about one-half its total width, is adapted to receive a small coin 20 edge-wise. The coin may be defined as a flat blunted-edged tool, and it will be appreciated that other flat thin objects may serve similarly. The slot is formed with parallel planiform sides spaced sufficiently to receive the edge of the coin 20 snugly therebetween, and one side 21 is of less height than the other. The high side forms a high right-angular shoulder 22 at its junction with the high half 23 of the top wall of the cap between the shoulder 22 and the rim 12. This top part 23 is substantially planiform and normal to the symmetrical axis of the bottle. The 20 opposite portion 24 of the top wall of the cap is inclined downwardly from the rim 12 to the low side of the slot. The bottom of the slot is sharply angular, and the tops of the walls of the slot form sharp, substantially right-angular 25 junctions with the respective top wall portions 23 and 24 of the cap. The operation of the coin in the proper direction, starting from an erect or perpendicular position induces the cap to rise easily for one-half of its area and snap off over 30 the rim of the bottle. This occurs in the following manner: The coin being set with its edge in the slot and firmly pressed edgewise thereinto, its upper free edge portion is pushed in the direction of the high side of the slot, as indicated 35 by the arrow in Fig. 2. The coin thus functions as a lever of the second order, the low side of the slot serving as a fulcrum, and work being largely done at the high shoulder 22 of the slot. In the continuation of this movement of the 40 coin, the top of the cap becomes deformed. The half 23 of the cap between the high side of the slot and the rim tends to be moved translatively in the direction of a diameter of the cap normal to and midway of the slot, and at the same time its portion immediately adjacent the slot is pressed downward, so that the outer part 23 of the cap, its rim, and its skirt rise and become free of the bottle. At the same time the 45 opposite part 24 of the cap, extending from the low side of the slot tends to be moved translatively on the same diameter as mentioned, but in an opposite direction, and to be pried upwardly adjacent the slot. The metal customarily used in crown caps is sufficiently thin to 50 enable the deformation described, and the weak-

ening crease 14 tends to permit opposite translatable movement of the two halves of the cap. The crease 14 marked superficially in the upper surface of the cap as a virtual continuation of the slot, enables this to be accomplished. The crease weakens the cap and affords a line on which half of the cap can readily bend, and then permit it to be detached from the rim 16 of the bottle. A cork disc gasket 15 with a slot-like opening 17 resiliently seals the space between the cap and the rim of the bottle and makes it liquid tight. The edges of the slot are preferably squared off as shown to provide a substantial fulcrum for the coin to lever on.

The crown seal or cap in this form is conveniently removable. It does not involve material additional cost to produce it over other types. It does not require any specially made tools for detaching, and it avoids the necessity of meddling with the scalloped edge 11. It also makes the cap so it cannot be replaced, which is a particular item where adulteration could be practiced.

While but one form of the invention is indicated in the drawings, it is not desired to limit the application for patent to such specific structure, as it will be appreciated, that other constructions could be used, that would embody the same principles and come within the scope of the appended claims.

Having thus described the invention, what is claimed is:

1. A cap for bottles comprising a dished, unsevered circular body of thin plate having a depending bead-clamping skirt, said body having an exterior transverse coin-fitting slot depressed in the top of the cap shaped to receive and fit a disc-like article and the like insertable therein, said slot having angular upper edges and being shaped to present a fulcrum edge at one side and a work edge at the other whereby the cap may be worked by the disc-like article by leverage movement of the disc-like article so as to displace substantial parts of the cap to positions at which the skirt parts are out of bead-clamping position.

2. The structure of claim 1 wherein the top

portion of the cap is impressed thereacross to form a crease extending from the slot to the skirt, to cause leverage motion in cap parts themselves in a direction to release the skirt from a bottle mouth bead, under leverage movement of the disc-like article against said fulcrum and work edges.

3. The structure of claim 2 in which the impressed crease is of a form to weaken the material of the cap and tend to cause opposite translatable movements of opposite parts of the cap along a diameter of the cap normal to said slot when said disc-like article is worked as a lever on said fulcrum and work edges.

4. The structure of claim 3 in which the side of the slot at said work edge is materially higher than the other, constituting a high shoulder, whereby in lever movement of said disc-like article said work edge will be greatly depressed and the skirt portion medially of the adjacent side of the cap will be swung outwardly at its lower part and upwardly from bead-clamping position.

5. The structure of claim 1 in which the side of the slot at said work edge is materially higher than the other, constituting a high shoulder, whereby in lever movement of said disc-like article said work edge will be greatly depressed and the skirt portion medially of the adjacent side of the cap will be swung outwardly at its lower part and upwardly from bead-clamping position.
